FLUID INJECTOR PUMP FOR MECHANICAL DISHWASHERS

Volney M. Jemison and Don H. Young, Phoenix, Ariz.

Application February 15, 1957, Serial No. 44,878

Term of patent 14 years

(Cl. D65—1)

Fig. 1

Fig. 2

Fig. 3

Fig. 4

Fig. 1 is a side perspective view of a fluid injector pump for mechanical dishwashers, showing our new design;

Fig. 2 is an elevational view of the side of the pump opposite that shown in Fig. 1; and

Figs. 3 and 4 are front and rear elevations, respectively, of the pump.

We claim:

The ornamental design for a fluid injector pump for mechanical dishwashers, as shown.
